DESIGN FOR A PLATE OR THE LIKE

Howard A. Silverman, Pittsburgh, Pa., assignor to
 Mayer China Company, Beaver Falls, Pa., a corporation of Pennsylvania

Application May 10, 1947, Serial No. 138,972

Term of patent 14 years

(Cl. D44—15)

To all whom it may concern:

Be it known that I, Howard A. Silverman, a citizen of the United States, residing at Pittsburgh, in the county of Allegheny and State of Pennsylvania, have invented a new, original, and ornamental Design for a Plate or the like, of which the following is a specification, reference being had to the accompanying drawing, forming part thereof.

In the drawing:

Figure 1 is a top plan view of a plate, showing my new design, an entire illustrative unit of which is contained within the annular lines. Said unit is repeated about the circumference of the plate.

Fig. 2 is a cross section on the line II—II of Fig. 1.

I claim:

The ornamental design for a plate or the like, as shown and described.

HOWARD A. SILVERMAN.
